CALENDAR WRITING INSTRUMENT

Leo Lowy, Brooklyn, N. Y.

Application August 5, 1936, Serial No. 94,459

1 Claim. (Cl. 40—108)

This invention relates to writing instruments and more particularly to a calendar attachment therefor.

An object of the present invention is to provide for application either to a mechanical pencil, fountain pen, or analogous writing instrument what may be termed a perpetual calendar.

A further object of the invention is to provide a writing instrument such as a fountain pen, pencil, or analogous instrument with a calendar, and wherein the instrument and calendar forming the part thereof is characterized by simplicity of construction, combination and arrangement of parts and facility of operation.

The invention together with its objects and advantages will be best understood from a study of the following description taken in connection with the accompanying drawings wherein:—

Figure 1 is an elevational view of a fountain pen embodying the features of the present invention.

Figure 2 is an enlarged detail sectional view taken substantially on the line 2—2 of Figure 1.

Figure 3 is a transverse sectional view taken substantially on the line 3—3 of Figure 2.

Figure 4 is an elevational view of the calendar per se.

Figure 5 is an end elevational view of the calendar.

Figure 6 is a longitudinal sectional view through the calendar cylinder.

Figure 7 is a perspective view of a cap member forming part of the invention.

Figure 8 is a view partly in section and partly in elevation illustrating the application of the invention to a mechanical pencil.

Figure 9 is a longitudinal sectional view through a pair of longitudinally separated calendar cylinders.

Figure 10 is an elevational view of a calendar cylinder.

Figure 11 is an end elevational view of a calendar cylinder on an enlarged scale.

Figure 12 is an elevational view of a calendar cylinder insert.

Figure 13 is a sectional view taken substantially on the line 13—13 of Figure 12, and

Figure 14 is a perspective view of a calendar roll.

Referring to the drawings by reference numerals and more particularly to Figures 1 to 7 inclusive, it will be seen that 5 indicates generally a fountain pen the barrel of which is indicated by the reference numeral 6.

In accordance with this form of the inven-

tion the barrel 6 at the end thereof remote from the point or nib of the pen is hollowed out and opened at one end to receive a calendar assembly indicated generally by the reference numeral 7.

In this form of the invention the calendar assembly 7 comprises, in the present instance, three nested calendar cylinders 8 formed of paper or other suitable material opened at one end and substantially closed at the opposite end, 10 and at said closed end provided with openings 9.

Each calendar cylinder 8 has arranged on its periphery as suggested clearly in Figure 4 calendar indicia 10, the calendar indicia 10 on each cylinder being sufficient for four (4) months 15 of the year. Also to readily identify the calendar cylinders 8 and the legendary matter carried thereby each cylinder 8 at the closed end thereof has printed or otherwise formed thereon the names of the four months constituting 20 the calendar indicia 10 on the periphery of the cylinder as will be clear from a study of Figures 4 and 5.

Further the calendar assembly includes a cap 11 adapted to be sleeved onto the open end portion of the nested calendar cylinders 8, and this cap 11 is formed on one end of a rod or bolt 12 that extends axially through the cylinders and through the openings 9. Threaded on the free end of the rod or bolt 12 is a nut 13 which cooperates with the cap 11 for securing the calendar cylinders and cap in assembled relation.

As shown in Figure 2 the calendar assembly 7 is placed within the free end of the barrel 6 with the cap 11 in abutting engagement with the end of the cylinder. At said end the barrel or cylinder 6 is provided with an elongated sight window 14 through which a part of the indicia 10 is exposed, the indicium 10 being so arranged that there will be exposed through the window 14 the name of the month and the day dates of a complete week of the calendar month. As shown in Figure 1 there may be suitably provided on the barrel 6 along one edge of the sight opening 14 the first letter of each of the days of the week.

It will be apparent that in operation the knob 11 is turned for bringing the proper longitudinal row of indicia opposite the window 14 at the proper intervals, and it will of course be understood that at the completion of the fourth 50 month the outermost calendar cylinder 8 will be removed so that the next adjacent calendar cylinder 8 is brought into use.

In Figures 8 to 11 inclusive is illustrated the application of the invention to a mechanical 55

pencil indicated by the reference numeral 15. In this form of the invention two calendar cylinders 16, 17, identical in construction, are provided and each is equipped on its periphery with 5 calendar indicia 18 germane to six months of the year so that after one cylinder has been used for the six months designated thereon the other cylinder is brought into use.

Each of the calendar cylinders 16, 17 is internally threaded at its respective opposite ends as 10 at 18 for the threaded reception of a knob 20.

In actual practice both cylinders are arranged in longitudinal alignment within the barrel of the pencil 15 with the cylinder having thereon 15 the indicia germane to the last six months of the year arranged in the forepart of the barrel about the lead feeding assembly 21 while the other cylinder, for example, the cylinder 17 having thereon the calendar indicia for the first six 20 months of the year is placed within the outermost end of the barrel 16 with the knob 20 threaded into one end of the cylinder 17 and having abutting engagement with the adjacent end of the barrel of the pencil as shown in Figure 8. At 25 said end the barrel 16 is provided, as in the case of the fountain pen, with a sight window 22 along one side of which are arranged the first letters of each of the seven days of the week.

As suggested in Figure 10 the calendar months 30 on the cylinders 16, 17 are arranged in groups of three one group being at one end of the cylinder and the other group at the opposite end. Thus it will be apparent that after the expiration of the 35 last day of the month of one group of months the cylinder being used is withdrawn from the barrel of the pencil, reversed, the knob 20 threaded into the reverse end of the cylinder and the cylinder replaced within the barrel to be used for calendar purposes during the next succeeding three 40 months.

As shown in Figure 9 the cylinders 16 and 17 are hollow to accommodate the reserve lead 23. As shown in Figure 8 the lead 23 is retained within the cylinder being used through the instrumentality of the head end of the lead feeding screw 21.

In Figures 12 to 14 there is shown a third form of the invention which may be used either with the fountain pen 5 or the pencil 15 and in this

form of the invention the calendar cylinders indicated by the reference numerals 24 are in the form of cylinders each of a diameter to carry on the periphery thereof indicia germane to three calendar months there being four of such cylinders 24. Cylinders 24 are longitudinally split as shown in Figure 14 and indicated at 25 and are nested together as shown for disposition within the barrel of the pencil or fountain pen as the case may be. 5

For the cylinders 24 there is provided a core member 26 which consists of a knob 27 to which are secured one end of a plurality of relatively spaced spring fingers 28 which are also secured at the end thereof remote from the knob 27 to a 15 head plate 29. The cylinders 24 are sleeved onto the core 26 to be held in expanded condition through the medium of the retaining fingers 28 and between the knob 27 and the head plate 29, and when the cylinders and core are assembled 20 the assembly may be placed within the end of the barrel of the pencil or fountain pen, as the case may be, to be used in substantially the same manner as the calendar cylinders constituting the first and second forms of the invention herein described in detail. 25

It is thought that a clear understanding of the construction, utility and advantages of an invention of this character will be had without a 30 more detailed description.

Having thus described the invention what is claimed as new is:—

In a writing instrumentality including a barrel open at one end and provided at said one end with an elongated sight window, a calendar unit 35 rotatably fitted within said end of the barrel and including a cylindrical member having calendar indicia thereon to be exposed through the sight window, said calendar indicia consisting of calendar months arranged in two laterally spaced 40 groups one of which is adapted to be exposed through the sight window in one position of the member and the other group being adapted to be disposed therethrough when the position of the member is reversed end for end and a knob 45 at the end of the barrel engageable with either end of the member for rotating same.

LEO LOWY.
